**EDGE GUIDE FOR FINNED TUBE BASEBOARD
HEATERS**

Karl O. Schleitner, Westchester, Ill., and Horace Wells Williams, Johnstown, Pa., assignors to Crane Company, Chicago, Ill., a corporation of Illinois
Filed Oct. 15, 1965, Ser. No. 496,525
7 Claims. (Cl. 165—55)

This application relates to finned tube heat exchange units and more particularly to edge guides therefor.

The conventional baseboard heat exchange unit, having fins mounted at closely spaced intervals along the length of the tube through which the heating medium is circulated, is contained in a substantially rectangular enclosure and is supported by resting the edges of the fins on brackets mounted in the enclosure perpendicular to the axis of the tube and to the enclosure wall on which the unit is mounted. During thermal expansion and contraction of the heat exchanger, the edges of the fins on the unit drag across the surfaces of the supporting brackets causing an objectionable scraping or "pinging" noise. In our invention, a nonmetallic parting member is disposed between the fins and each support bracket, effectively removing any undesirable scraping sounds which may result during thermal expansion and contraction of the unit.

In the accompanying drawings, we have illustrated certain presently preferred embodiments of our invention in which:

FIGURE 1 is a partial perspective view of a heat exchange unit embodying our invention.

FIGURE 2 is a partial perspective view showing our invention positioned on the heating unit support.

FIGURE 3 is an enlarged plan view of our invention.

FIGURE 4 is an enlarged front elevation view of our invention.

FIGURE 5 is an enlarged side elevation view of our invention.

FIGURE 6 is a fragmentary section taken along the lines VI—VI of FIGURE 4.

FIGURE 7 is an enlarged bottom view of our invention.

Referring to FIGURE 1, a heat exchange unit 8 comprises a medium conducting tube 9 and a plurality of rectangularly shaped fins 10 mounted normal to the tube 9 at closely spaced intervals along the outer surface of the tube length. The unit 8 is contained in a metal enclosure 11 having a vertical back wall 12 and a substantially vertical front wall 13, shown in shadow on the drawing. A bracket support 14 having a vertical arm 15 attached to the back wall 12 and a horizontal arm 16 extending perpendicular to the arm 15 and to the back wall 12 and normal to the axis of the tube 9 supports the heat exchange unit 8. An upper arm 17 parallel to said horizontal arm 16 and in the same vertical plane as the arm 16 extends perpendicular to the back wall 12 of enclosure 11 and is vertically spaced from the horizontal arm 16. The front wall 13 of the enclosure is adapted to engage arms 16 and 17 to complete the enclosure of the heat exchange unit 8.

The horizontal arm 16 of the bracket support 14 extends from the back wall 12 beneath and parallel to the fins 10 a distance sufficient to include the vertical components 18 of a pair of angle-shaped nonmetallic parting members 19 of edge guides 20 between the back wall 12 and the outer end 21 of the horizontal support arm 16. Each guide 20 is positioned on the horizontal arm 16 with the vertical component 18 of the parting member 19 along the side edges of the fins and with the guide length parallel to the longitudinal axis of the conducting tube 9 such that the edges of the fins 10 rest in the angle shape of the parting member 19. Moreover, the length of the

2

parting member is greater than the width of the horizontal support arm 16, therefore, no portion of the arm 16 can contact the fins 10 of the heat exchange unit 8.

As shown in FIGURE 2, a pair of edge guides 20 are positioned on the horizontal support arm 16, each guide 20 having a parting member 19 including a vertical component 18 and a horizontal component 22. A stud element 23 of width sufficient to frictionally contact the opposing faces of adjacent fins extends vertically upward from the horizontal component 22 of the member 19. Since the width of each stud element closely approximates the space between opposing surfaces of adjacent fins, movement or "play" between the heat exchange unit and the edge guide is eliminated when the guide is in position along the fins. During thermal expansion and contraction of the heat exchange unit, the unit and the edge guides "ride on" or slide across the horizontal bracket support arms without undesirable noise.

The detail structure of our preferred edge guide is shown in FIGURES 3—7 of the drawings.

Referring to FIGURE 3, the vertical stud element 23 located on the horizontal component 22 of the parting member 19 is a hollow extruded member, generally of cylindrical cross-section, having flats 24 for frictional contact with opposing faces of adjacent fins of a heat exchange unit. FIGURE 3, as well as FIGURE 7, also shows openings 25 outside the opposed flats 24 which openings provide the clearance required for the mandrel (not shown) used in extruding the vertical stud element 23 shown in our preferred embodiment.

FIGURE 4, particularly, illustrates the shape of the vertical stud element 23, showing the reduced cross-sectional area of that portion of the stud element adjacent the horizontal component 22 of the parting member 19. Where, as in some conventional baseboard heating units, opposing faces of adjacent fins have reinforcing ribs extending generally horizontally from the outside edges of the faces, the shoulder portion 26 of stud element may be seated on the upper edges of such reinforcing ribs to provide locking engagement between the fins and the edge guide. The sectional view, in FIGURE 6, of the reduced portion of the stud element 23 points up the limited attachment area between the horizontal component 22 and the vertical stud element 23.

To provide a smaller contact area between the edge guide 20 and the horizontal arm of the bracket support, thereby reducing the possibility of noise arising from the moving contact between the guide and the bracket support arm, we have also included in our preferred embodiment, as shown in FIGURES 4, 5 and 7, a longitudinal raised rib portion 27 on the underside of the horizontal component 22 of the parting member 19. During movement of the unit, the rib portion 27, which is longer than the width of the horizontal arm and extends substantially the entire length of the horizontal component of the parting member, enables the guide to slide smoothly on the horizontal bracket support arm. FIGURE 5 is especially illustrative of the position of the rib portion 27 on the bottom of the horizontal component 22 of the parting member 19 between the vertical stud element 23 and the vertical component 18 of the parting member.

It is evident from the foregoing description that our guide is easy to attach to a finned heating unit to eliminate any undesirable scraping noise which might occur during thermal expansion and contraction of the unit. Further, since conventional forming methods may be used in making our guide, it can be inexpensively fabricated in any desired quantity.

While we have described the presently preferred embodiments of our invention, it is to be understood that it may be otherwise embodied with the scope of the following claims.

We claim:

1. An edge guide in a baseboard heating unit, said unit having a heat exchange unit having a medium conducting tube with a plurality of fins mounted at close intervals on the outer surface of the tube and extending at an angle to the tube, said fins having bottom and side edges and adjacent fins having opposed faces, an enclosure for the heat exchange unit, and a support within the enclosure for the heat exchange unit, said support having a horizontal arm extending beneath the bottom edges of the fins to support said heat exchange unit, said guide comprising

(A) an angle shaped nonmetallic parting member adapted to be positioned between the horizontal arm of said support and the bottom edges of said fins and having

- (a) a vertical component to extend along the side edges of said fins, and
- (b) a horizontal component to extend along and in contact with the bottom edges of said fins
- (c) said angle-shaped member having a length greater than the width of the horizontal arm of said support, and

(B) a stud element extending vertically upward from said horizontal component between adjacent fins and to frictionally engage the opposed faces of said fins to hold the edge guide on the fins.

2. An edge guide as described in claim 1 in which the parting member is a piece of plastic material.

3. An edge guide as described in claim 1 in which the parting member is polyethylene.

4. An edge guide as described in claim 1 in which the stud element is substantially circular in cross-section and

has opposed flats which engage opposed faces of adjacent fins.

5. An edge guide as described in claim 1 in which the stud element is integral with the parting member, the horizontal component of said parting member having clearance near the base of said stud element to accommodate a mandrel for extruding said stud element.

10 6. An edge guide as described in claim 1 and having a rib portion on the underside of said horizontal component between said stud element and said vertical component, the length of said rib portion being greater than the width of said horizontal arm, said rib portion adapted to be in sliding contact with said arm.

15 7. An edge guide in a baseboard heating unit as described in claim 1 in which opposed faces of adjacent fins have generally horizontally extending reinforcing ribs and in which said stud element has a shoulder portion spaced from the horizontal component of the parting member a distance substantially equal to the upper edges 20 of said ribs, the cross-section of said shoulder portion being greater than the space between opposed ribs on the fins to seat on said ribs thereby providing locking engagement between said shoulder portion and said adjacent fins.
